UNITED STATES PATENT OFFICE.

AUGUSTE ROBERT MÜLLER, OF WALTHAMSTOW, ENGLAND.

ELECTRIC INSULATOR.

1,159,469.

Specification of Letters Patent.

Patented Nov. 9, 1915.

Application filed June 15, 1912. Serial No. 703,933.

To all whom it may concern:

Be it known that I, AUGUSTE ROBERT MÜLLER, a subject of the German Emperor, residing at 56 Shernhall street, Walthamstow, in the county of Essex, England, have invented new and useful Improvements in Electric Insulators, of which the following is a specification.

This invention relates to improvements in electric insulators adapted for use with wires carrying heavy currents and consisting of a plurality of members.

According to this invention I construct a member of an insulator with an internally screw threaded recess and a screw threaded projection of the same diameter. The members are secured together by screwing the projection on one into the recess of another. The insulators may be secured to stalks which are supported by or depend from arms or the insulator is secured between two arms in which case the insulator is duplicated. Preferably the wire is held in a groove in the member by a block secured in position by another member. Such insulators are interchangeable and are stronger than those made in one piece and in consequence of the air spaces formed by the grooves they do not break owing to changes of temperature as is now the case.

Figures 1, 2, 3, 4 and 5 illustrate different forms of insulators made in accordance with this invention; all the figures are elevations partly in section.

The insulator shown in Fig. 1 consists of three members *c*, *h* and *e*, the member *h* being provided with an internally screw threaded socket and a screw threaded projection of the same diameter and also a

groove *b*. The wire *a* is held in the groove *b* in the member *h* by a block *d* secured in position by the cap *e*.

Fig. 2 is similar to Fig. 1, but in this case a member *i* of a different shape to the member *h* is substituted for it.

Fig. 3 shows an insulator made of three members *c*, *h* and *i* and a cap *e*.

Fig. 4 shows an insulator secured between two arms *j*. As before the wire *a* is held in a groove *b* in the member *i* by a block *d* secured in position by the member *c*. Onto the members *i* and *c* are screwed similar members *h*, onto which are screwed other similar members *i* and *c*, the member *i* being placed at the top. The members *i* and *c* are secured to the arms *j* by stalks *k* and *l* respectively.

Fig. 5 shows an insulator similar to that shown in Fig. 4 except that the members *h* are omitted.

Such insulators are stronger than those made in one piece and in consequence of the air spaces formed by the grooves they do not break owing to changes of temperature as is now the case.

What I claim is:

An insulator, consisting of a plurality of connected members each made of insulating material and each having a wire-receiving and ventilating groove across the top, an internally screw-threaded recess and a screw-threaded projection of the same diameter as the recess, the projection of one member being received by the recess of the adjacent member, and a block of insulating material secured in the groove of one member by the projection of an adjacent member.

AUGUSTE ROBERT MÜLLER.
